UNITED STATES PATENT OFFICE

147,320

DESIGN FOR A BABY WALKER OR SIMILAR ARTICLE

John D. Cuccio, Los Angeles, Calif.

Application March 18, 1946, Serial No. 127,641

Term of patent 7 years

(Cl. D15—1)

To all whom it may concern:

Be it known that I, John D. Cuccio, a citizen of the United States, residing in Los Angeles, in the county of Los Angeles, State of California, have invented a new, original, and ornamental Design for a Baby Walker or Similar Article, of which the following is a specification, reference being had to the accompanying drawing, forming a part thereof.

The characteristic features of my design reside in the portions shown by means of full lines in the drawing.

I claim:

The ornamental design for a baby walker or similar article, as shown and described.

JOHN D. CUCCIO.
